APPARATUS AND METHOD OF TRANSFERRING COKE AND COAL OR THE LIKE

Filed Oct. 26, 1927

UNITED STATES PATENT OFFICE

HENRY ADAMS, OF PLAINFIELD, NEW JERSEY

APPARATUS AND METHOD OF TRANSFERRING COKE AND COAL OR THE LIKE

Application filed October 26, 1927. Serial No. 228,841.

This invention relates to apparatus and methods for transferring coal, coke or the like from one storage place to another whereby the breakage and degradation of the material produced in the transfer is reduced to a minimum.

Another object of this invention is to transfer the material from one storage place to another storage at a lower level, and during the transfer to maintain a continuous stream of material which is always under control of the operator and at no time allowed to travel at an excessive velocity, nor is it allowed to fall any distance, thereby reducing the breakage and degradation to a minimum.

Another object of this invention is to provide means and methods of this kind that can be adapted and used with the present already built railroad transfer for transferring from cars to boats or barges, and which can be installed in these present plants at a nominal cost, utilizing the present plants, which are very costly to build.

This invention particularly relates to the transferring of coal or coke and the like from railroad cars when the car is tilted over and a large body of coal or coke is transferred very rapidly into boats or barges; and in order to help make the invention particularly clear, mention is here made of the loader at present well known and used in making this transfer, operation of which is described as follows:—

A railroad trestle is built at or near the dock where the boat or barge is to be loaded. This trestle is so constructed that the loaded coal car can be tipped over so contents run into a large inclined triangular chute which is attached to the railroad trestle. This chute which is wide at the upper end and laterally tapered to the lower end, is filled and carries away the coal from the car into a collapsible telescopic lowering chute which is lowered down in the bottom of the barge. This telescopic chute can be raised or lowered or swung from side to side at the will of the operator.

The main object of the present invention is to do away with the excessive leakage and

degradation inherent in the operation of the above mentioned well known loader now in use, the operation of said known loader being as follows:

The entire car is tilted and turned over, 55 and as the car is tilted to above the chute the top coal will rush out of the car and strike the large triangular chute which is placed at an angle of from 30 to 50 degrees at a very high velocity causing very excessive degradation. 60 The coal then travels at a very high rate of speed down toward the narrow lower end portion of the chute, the depth of the coal increasing at the bottom.

It will be noted that intermediately the 65 depth of the coal is not great but as the coal travels down toward the narrow portion of the chute, the thickness or the depth, of the coal increases at the lower end, which is the narrowest portion of the chute. The lower 70 end portion of the chute is covered by plates, and here there is a solid bank of coal filled to the top and only held in the chute by means of the plates. The upper middle portion of the chute becomes practically empty as soon 75 as car is empty, whereas the lower portion of the chute is full. As this coal travels from the car down to the end of the chute it gains great velocity and strikes against the interiorly open vertical telescopic chute at the 80 lower end of the triangular chute where it is subjected to greater breakage owing to the great velocity of the coal as it strikes the vertical chute, so much so that when a car is unloaded a cloud of dust comes from this particular spot. The coal on reaching this spot, 85 now falls perpendicularly down the telescopic chute to the bottom of the barge, this fall being from 20 to 30 feet. The telescopic chute rests on the bottom of the barge, and 90 here excessive breakage is again encountered until the entire chute is filled.

It will thus be noted that there are great degradation and breakage in this part of the old operation, and my new apparatus and 95 method are designed to overcome these. From this time on there is not very much breakage in the old operation of the coal of the car that has been thus emptied, but as the railroad cars hold only 50 tons of coal, the 100

operator having the telescopic chute filled with coal, as soon as the triangular chute is empty, does not allow any more coal to flow out of chute and another railroad car is dumped into the triangular chute where the coal will have the same breakage going into the chute and down to the bottom of the triangular chute as it would in the first car, but the coal from the second car will not be subjected to any breakage by falling from the top to the bottom of the telescopic chute, as this latter chute is already full, but as the boats or barges are divided by partitions it is necessary as soon as one partition is filled to move the boat or barge, and when this is done the telescoping chute must be lifted free and clear of the barge, and when this is done the telescoping chute must be entirely emptied of coal, and when the car is dumped into the new compartment the first 10 or 15 tons will receive an addition to the excessive breakage caused in the triangular main chute, the additional excessive breakage from the fall of coal from the top of the telescoping chute down to the bottom of the barge until telescoping chute is filled.

This explanation is made so that it is clearly understood how much degradation there is when coal is handled as at the present time, in the most modern plants of railroad transfers, which are very expensive to erect. The above clearly shows the excessive breakage of the coal and as there can be no gate at the bottom of the telescoping chute, at no time has the operator any control of the outlet at the bottom of the chute, unless he keeps the chute directly on top of the coal; and when the boat or barge is moved, there is no possible means of retaining the column of coal in the telescoping chute, so whenever the boat or barge is moved, excessive breakage is caused by coal falling from the top to the bottom of the telescoping chute.

By my improved method and apparatus, the breakage has been reduced as much as 25 percent; and other objects are to reduce the expense and time of unloading, the time being reduced to a few seconds for each car.

Other objects of the invention are to improve generally the simplicity and efficiency of such methods and apparatus and to provide an apparatus of this kind which is rapid, economical, durable and reliable in operation, and economical to construct.

Still other objects of the invention will appear as the description proceeds; and while herein details of the invention are described and claimed, the invention is not limited to these, since many and various changes may be made without departing from the scope of the invention as claimed in the broader claims.

The inventive features for the accomplishment of these and other objects are shown herein in connection with an improved mate-

rial transferring apparatus which, briefly, stated, includes means to tip the car over on one edge thereby to empty the car into a downward and forwardly inclined and pointed chute having its upper edge disposed along 70 said edge of the car, said chute having converging side walls and a lower discharge end similar to the old apparatus above mentioned.

A cover disposed over the chute carries at its upper edge a baffle plate extending to near 75 the upper edge of the tipped up car, for admitting material to the chute at the lower edge of the car only.

A retarding apparatus in said chute includes a plurality of converging partitions 80 substantially perpendicular to the floor of the chute and substantially radial to said lower end, and transverse retarding baffles passed through said partitions a short distance above, and converging toward, the floor. 85

A vertically adjustable vertical chute pivotally mounted on said discharge end and communicating with said discharge end and having a lower discharge gate, is somewhat similar to that described in my co-pending 90 application No. 162,134 filed Jan. 19, 1927.

As the material is lowered from the tipped-over car the upper baffle plate confines the flow of material to a limited space near the lower edge of the car and retards it as it leaves the car. Then the partitions divide and lower the material in a plurality of adjacent streams and laterally frictionally engage the streams for retarding the material also laterally compressing and converging and thereby additionally retarding the material of the streams as it is lowered, where it is baffled and retarded by the transverse baffles before it is delivered to the vertical chute. 105

In the accompanying drawing, showing by way of example, one of many possible embodiments of the invention.

Fig. 1 is a longitudinal vertical sectional view, partly in elevation, showing the apparatus transferring material to a barge; and 110

Fig. 2 is a plan of the apparatus, part being in section.

My improved apparatus is shown in combination with a tressle 5 carrying a railroad track 6 thereon on which is carried a coal car 7 with which is associated a car tipple means 8 pivoted, as at the axis 9, at the upper edge of one side of the car and engaging under the car and adapted to tip the car over said axis for emptying the coal or other material therefrom, as shown by the dotted line of Fig. 1, into a downwardly and forwardly inclined and pointed triangular chute 10 having the upper edge of its inclined floor disposed and pivoted along axis 9 at said edge of the car and provided with converging side walls 11 co-operating at the lower end with the floor to form a discharge end 12 on which is disposed a lower cover plate 130

mounted on the side walls over the discharge end portion of the chute.

5 A hoisting cable 13 secured to the lower edge of the chute is disposed over a pulley 14, whereby the chute may be pivotally raised and lowered. The apparatus as just described is similar to the above mentioned known apparatus already in use.

10 A retarding apparatus disposed in said inclined chute comprises a false bottom 17 lying on the floor of the inclined chute and carries side walls 18 disposed against the side walls of the chute 11, said apparatus extending from side to side and substantially 15 from the top edge of said floor to near said cover plate 12.

120 A plurality of converging contracting partitions 20 secured on said false bottom all point substantially radially toward the lower end of the chute and extend from the top edge to the bottom edge of the false bottom 17.

20 Converging plates 21 between said partitions 20 extend from the bottom edge of the false bottom to about halfway up the false bottom.

22 Transverse retarding baffles 22, 23 pass through said partitions 20 just above the converging plates 21 and through the converging plates 20 and partitions 21, and extend all the way across the retarding apparatus to the side walls thereof. They are spaced a short distance from said false bottom 17 and downwardly converge toward 25 said bottom at an angle of about 25 to 35 degrees.

An upper cover plate 25 disposed over the retarding apparatus and resting on the side walls of the chute and extending from the 40 lower plate 12 to the upper edge of the chute, carries a baffle plate 26 fixedly mounted on the upper edge of the cover plate 25 and extending substantially even with the upper edge 27 of the car when in tipped position 45 to retard and guide into the chute the material as the car is tipped.

50 A support 30 fixedly secured to the lower end of said chute is provided with an extension housing 31 at the forward end, and adjacent to the inclined chute with side members 32 forming a large opening 33 in which is disposed an axially vertical guide box 34 hinged at 34' (Fig. 1) to the lower face of the inclined chute and provided with a rear opening 34" communicating with said discharge end of the chute. Said box 34 slidably receives a vertically adjustable floating chute 35 having lower discharge gates 36 and a downwardly and outwardly inclined floor 37 extending to said gate. Said chute 35 has opposite side walls 40 and an outer wall 41, leaving an open side 42 communicating with said inclined chute.

55 Pulleys 43, 43' placed on said support to the front and rear of the chute receive flexible

means such as cables 44, 44' each having one end connected to the lower end of the chute 35 and the box 34 respectively, the upper end portions being separately connected to a hoisting motor 45 carried in said extension housing 31 whereby said chute may, by means of the cable 44, be easily lowered into or gradually raised from a suitable receptacle 46 such as a boat, truck, bin car or the like to be loaded or left in any position of vertical adjustment, or be swung from side to side by means of the cable 44, the weight of the chute tending to swing it against the action of the cable 44'.

70 The curved slide gates 36 disposed across said lower opening of the vertical chute have side arms 47 co-axial with the curve of the gate and pivoted to the side walls of the vertical chute, whereby the gates may be easily operated.

75 Said open side 42 of the vertical chute is provided with a vertical series of downwardly and inwardly inclined retaining plates 50 secured fast between said side walls 40 perpendicular thereto and extending substantially 80 from top to bottom of the chute, spaced from said outer wall 41 to form a vertical passage 51 at said outer wall. The retaining plates 50 extend to said open side, whereby the retaining plate nearest the lower edge of the inclined chute may receive material therefrom and direct it into the vertical passage 51, thereby to fill the passage up to the inclined chute and then to pile up the material in the inclined chute to prevent the flow of coal except as controlled by the gates 36 and the material piling beneath the vertical chute 35, as the latter, initially at the bottom of the barge, is gradually raised.

85 The lower inner edge of each plate 50 is below the level of the top edge of the next lower plate, a distance depending upon the particular material, to prevent the material from flowing to the open side thereby providing a void at said side.

90 The chute 35 may be raised with the gates 36 closed, and the chute gradually filled and lowered the gates being opened after the chute is lowered to the bottom of the receptacle, whereupon the material is deposited upon the floor of the barge the chute being gradually raised only as the barge fills and the body of material in the chute rests on the material in the barge.

95 The part 55 of the box 34 below the opening 34" forms a deflecting baffle secured to the under face of said discharge edge and downwardly extending more than the vertical distance between the retaining plates with its lower edge clearing the retaining plates as the chute is raised. This baffle 55 serves to deflect into the chute any material which may fall from the uppermost active retaining plate as the chute is raised. The chute 35 is similar to that shown and claimed in my co- 100

pending application Serial No. 162,134, filed Jan. 19, 1927.

It will be seen that my new apparatus is similar to the old plants already in use with the addition of the partitions and plates 20, 21 and the baffles 22, 23 and 26; and instead of having a telescopic chute I use the floating chute, shown in my said application. This floating chute has the gates 36 and can be moved from one side to the other by the operator by means of the flexible means 44'. The operator also can raise or lower this chute at will, which is shown in a raised position by the dotted lines in Fig. 1. The operator raises the chute as the barge fills up. The operator also, by means of the gates 36 can always maintain a column of coal in the chute 35 regardless of its position.

The operation is as follows:

The car 7 of coal or the like is tipped over, and the baffle plate 26 keeps the coal from falling down into the chute 10 and causes the coal to pass underneath this baffle in an even flow. In this chute 10, the partitions 25 and baffles 22 will cause the coal from the car to be divided into four separate streams, all of these streams coming together at the lower end of chute 10, tending to retard the velocity. About one-halfway down the partitions 30, the extra converging plates 21 again separate the central portion of the coal, which tends to travel more or less in a straight line, into more divisions, thus further retarding this middle portion of the coal. This is necessary as the middle portion would travel faster than the outside portion if this were not done.

The line of travel of the coal down main chute is shown in Fig. 1, and it will be noted that the depth of coal is greatest at the lower edge of the baffle plate 26 and gradually diminishes or remains about the same depth in the lower part of the inclined chute. In other words the main portion of the work of the chute is accomplished in the upper and middle part, whereas in the old plants, the main work is done at the discharge end. In the present invention, the travel of the coal is not of excessive velocity and the breakage, when the coal reaches the upright chute 35 is greatly reduced. As the chute 35, often can always be kept filled with coal by means of the gates 36 after it is once filled, there will not be any breakage caused by the coal falling from chute 10 to the bottom of the barge.

It has been found that the travel of the coal from the car to the chute 35 takes longer in the present invention than it does in the old plants, but this does not interfere materially or slow down the operation, for before a new car can be brought back to the railroad trestle and dumped to main chute 10, the main chute will be practically cleared of the coal of the first car.

It is obvious that the breakage is greatly reduced in three separate and distinct places.

In the old method, the location of excessive breakage is right at the car being emptied and at the top and bottom of the telescoping chute. In the present invention the breakage at the baffle plate 26 has been practically eliminated; 70 the breakage at the juncture with the vertical chute has been very materially reduced, and there will be no breakage in the vertical chute after the vertical chute has been once filled.

It is obvious that the new retarding apparatus can be cheaply and easily placed in the main chute of railroad coal transfers now in use (which were very costly to build), and by means of this invention change them into 80 transfer points, whereby coal can be unloaded from the cars into the barges, maintaining at all times a solid column of coal from car to barge and handling it in such a manner that the present excessive breakage, which 85 runs into millions of dollars per year, will be greatly reduced.

I claim as my invention.

1. A method comprising dividing material to be lowered into separate inclined streams; 90 and gradually lowering and laterally compressing the streams to retard the flow, while maintaining the major part of the upper face of the stream substantially unengaged.

2. A method comprising dividing material to be lowered into separate inclined streams; 95 and gradually lowering and laterally frictionally engaging the streams to retard the flow, while maintaining the major part of the upper face of the stream substantially unengaged. 100

3. A method comprising dividing material to be lowered into separate inclined streams; and gradually lowering, laterally compressing and frictionally engaging the streams to 105 retard the flow, while maintaining the major part of the upper face of the stream substantially unengaged.

4. A method of lowering material, said method comprising dividing and gradually 110 lowering the material in a plurality of adjacent inclined streams; baffling and laterally frictionally engaging the streams for retarding the streams; and laterally compressing and converging the material of the streams as 115 it is lowered, while maintaining the major part of the upper face of the stream substantially unengaged.

5. In combination, a wide downwardly inclined chute having an open upper edge, an 120 inclined floor in a single plane, side walls, and a lower discharge end; and spaced partitions in said chute pointing toward said end.

6. In combination, a downwardly and forwardly inclined and pointed chute having 125 an open upper edge, an inclined floor in a single plane, converging side walls and a lower discharge end; and a retarding apparatus in said chute including a plurality of partitions converging toward said lower end; 130

the inclination of the floor being steeper than and approximating the angle of repose of the material thereon.

7. In combination, a wide downwardly inclined chute having an open upper edge, side walls, and a lower discharge end; a retarding apparatus in said chute comprising a plurality of spaced partitions secured substantially perpendicular to the floor, all pointing toward said lower end and extending from near the top to near the bottom of the floor; and division plates about half way between said partitions extending about half way up the partitions.

15 8. In combination, a wide downwardly pointed and inclined chute having an open upper edge, converging side walls, and a lower discharge end; a retarding apparatus in said chute comprising a plurality of converging partitions secured substantially perpendicular to the floor of the chute, all pointing toward said lower end and extending from near the top to near the bottom of the floor; and converging plates about half way between 20 said partitions extending about halfway up the partitions.

25 9. In combination, a wide downwardly inclined chute having an open upper edge, side walls, and a lower discharge end; and transverse retarding baffles in said chute and fixedly spaced a short distance above, and converging toward the floor.

10. In combination, a wide downwardly pointed and inclined chute having an open upper edge, converging side walls, and a lower discharge end; and transverse retarding baffles in said chute fixedly spaced a short distance above, and converging toward, said floor.

40 11. In combination, a wide downwardly inclined chute having an open upper edge, side walls, and a lower discharge end; a retarding apparatus in said chute comprising a plurality of spaced partitions secured substantially perpendicular to the floor, all pointing toward said lower end and extending from near the top to near the bottom of the floor; division transverse retarding baffles passed through said partitions.

50 12. In combination, a wide downwardly inclined downwardly pointed chute having an open upper edge, converging side walls, and a lower discharge end; a retarding apparatus in said chute comprising a plurality of spaced partitions secured substantially perpendicular to the floor, all pointing toward said lower end and extending from near the top to near the bottom of the floor; and transverse retarding baffles passed through said partitions.

60 13. In combination, an inclined downwardly pointed chute having its upper edge disposable along the edge of a tipped-over car, said chute having side walls and a lower discharge end; a retarding apparatus in said chute including a plurality of converging

partitions; converging plates about midway between said partitions extending from near the lower end of the partitions to about halfway up the partitions; and transverse retarding baffles passed through said partitions just above the converging plates and through the converging plates and partitions, and extending all the way across the retarding apparatus, and spaced a short distance from said floor of the chute and downwardly converging toward said bottom at an angle of about 25 to 35 degrees.

70 14. In combination, a wide downwardly inclined chute having an open upper edge, side walls, and a lower discharge end; a false floor in said chute, and a retarding apparatus on said floor.

80 15. In combination, an inclined downwardly pointed chute having its upper edge disposable along the edge of a tipped-over car, said chute having converging side walls and a lower discharge end; and a retarding apparatus in said chute including a false bottom lying on the floor of the inclined chute and side walls disposed against the side walls of the chute, said apparatus extending from side to side and substantially from the top edge of said floor to near said lower end; and a retarding means on said floor.

85 16. In combination, a wide downwardly pointed and inclined chute having an open upper edge, converging side walls, and a lower discharge end; a false bottom lying on the floor of the inclined chute and side walls disposed against the side walls of the chute, said apparatus extending from side to side and substantially from the top edge of said floor to near said cover plate; and a plurality of converging contracting partitions secured on said false bottom all pointing toward the lower end of the inclined chute and extending from top to bottom edge of the false bottom.

90 17. In combination, means to tip a car on one edge; a downwardly and forwardly inclined chute having its upper edge disposed along said edge, said chute having side walls and a lower discharge end; and a baffle above the upper edge of the chute extending toward the upper edge of the car when tipped.

110 18. In combination, a car tipple means adapted to tip the car over on one edge for emptying material therefrom; a wide downwardly and forwardly inclined chute having the upper edge of its floor disposed along said edge, said chute having side walls cooperating with the floor to form a lower discharge end; cover plates on the walls covering the chute from the discharge portion to the upper edge portion; and a baffle plate on the upper edge of the cover plate 115 extending substantially to the upper edge of the car when tipped.

120 19. In combination, a wide downwardly pointed and inclined chute having an open upper edge, converging side walls, and a 130

lower discharge end; a support fixedly secured to said lower end and provided with an extension housing at the forward end and adjacent to the chute with side members co-operating to form a large opening; an axially vertical guide box pivoted in said opening; a vertically adjustable floating chute in said guide box having a lower discharge gate and an open side communication with said end; pulleys disposed on said support to the front and rear of the chute; and flexible means disposed over the pulleys and having their lower ends connected to the lower ends of said box and vertical chute respectively, the upper end portions being separately connected to a hoisting motor carried in said extension housing whereby said chute may be lowered into or gradually raised from a suitable receptacle such as a boat or the like or left in any position of a vertical adjustment or swing from side to side.

20. In combination, a wide downwardly pointed and inclined chute having an open upper edge, converging side walls, and a lower discharge end; and means at the mid part of the chute remote from the side walls for retarding the flow of material in the chute.

21. A method comprising gradually lowering the material in a wide path open at its upper longitudinal face; laterally compressing and frictionally engaging the material to retard the flow while maintaining the material substantially unengaged throughout the major portion of said face; and additionally retarding the flow near the middle axis of the path.

22. A chute for coal, coke and like material comprising an inclined downwardly pointed floor; converging side walls co-operating with the floor to form a narrow lower discharge end; and partitions in said chute pointing toward said end and co-operating with each other and the side walls to form a plurality of narrow passages tapering and pointing toward said end; the steepness of said floor and the distance apart of said partitions and walls being such that all parts of the material will flow slowly to the discharge end without intermediately banking up in the passages.

23. In combination, a downwardly inclined relatively shallow chute having downwardly converging side walls and a lower discharge end; and a retarding means in said chute remote from the side walls thereof.

24. In combination, an inclined downwardly tapered chute having its upper edge disposable along, and substantially as long as, the edge of a tipped-over car, said chute having downwardly converging side walls and a lower discharge end; and a retarding means in said chute remote from the side walls thereof.

25. A chute for coal, coke and like ma-

terial comprising an inclined downwardly pointed floor; side walls downwardly converging throughout and co-operating with the floor to form a narrow lower discharge end; partitions in said chute pointing toward said end and cooperating with each other and the side walls to form a plurality of narrow passages downwardly tapering throughout and pointing toward said end; the steepness of said floor and the relative angle and distance apart of said partitions and walls being such that all parts of the material will flow slowly to the discharge end without intermediately banking up in the passages; and means for retarding the material discharged from said discharge end.

Signed at New York, in the county of New York and State of New York, this 24th day of October, A. D. 1927.
